US00D357911S

United States Patent [19]

Grant et al.

[11] **Patent Number:** Des. 357,911[45] **Date of Patent:** ** May 2, 1995[54] **COMPUTER KEYBOARD**

- [75] Inventors: **Alan H. Grant**, Chevy Chase, Md.;
Eugene A. Helmetsie, Spencer, N.Y.
- [73] Assignee: **Ergonomics, Inc.**, Chevy Chase, Md.
- [**] Term: **14 Years**
- [21] Appl. No.: **22,402**
- [22] Filed: **May 4, 1994**

Primary Examiner—Freda S. Dunn*Attorney, Agent, or Firm*—Jacobson, Price, Holman & Stern[57] **CLAIM**

The ornamental design for a computer keyboard, as shown and described.

DESCRIPTION

FIG. 1 is a top plan view showing our new design for a computer keyboard with the broken lines being shown for illustrative purposes only and forming no part of the claimed design;

FIG. 2 is a front elevational view thereof;

FIG. 3 is a rear elevational view thereof;

FIG. 4 is a bottom plan view thereof;

FIG. 5 is a right-hand side elevational view thereof;

FIG. 6 is a left-hand side elevational view thereof;

FIG. 7 is a right-hand side elevational view of the keyboard raised at the front;

FIG. 8 is a right-hand side elevational view of the keyboard raised at the rear;

FIG. 9 is a raised front elevational view thereof; and,

FIG. 10 is a raised rear elevational view thereof.
